(57) **CLAIM**

The ornamental design for a water bottle, as shown and described.

DESCRIPTION

FIG. 1 is a perspective view of a first embodiment of a water bottle, with its cap on, showing the claimed design; FIG. 2 is a top view thereof;

FIG. 3 is a front view thereof; and

FIG. 4 is a side view thereof.

FIG. 5 is a perspective view of a first embodiment of a water bottle, with its cap removed, showing the claimed design; FIG. 6 is a top view thereof;

FIG. 7 is a front view thereof; and

FIG. 8 is a side view thereof.

FIG. 9 is a perspective view of a second embodiment of a water bottle, with its cap on, showing the claimed design; FIG. 10 is a top view thereof;

FIG. 11 is a front view thereof; and

FIG. 12 is a side view thereof.

FIG. 13 is a perspective view of a second embodiment of a water bottle, with its cap removed, showing the claimed design;

FIG. 14 is a top view thereof;

FIG. 15 is a front view thereof; and

FIG. 16 is a side view thereof.

FIG. 17 is a perspective view of a third embodiment of a water bottle, with its cap on, showing the claimed design; FIG. 18 is a top view thereof;

FIG. 19 is a front view thereof; and

FIG. 20 is a side view thereof.

FIG. 21 is a perspective view of a third embodiment of a water bottle, with its cap removed, showing the claimed design;

FIG. 22 is a top view thereof;

FIG. 23 is a front view thereof; and,

FIG. 24 is a side view thereof.

The broken lines in the drawings depict portions of the water bottle that form no part of the claimed design.
